UNITED STATES PATENT OFFICE

2,604,536

TELEVISION CABINET HAVING VIEWING
TUBE HOUSING ROTATABLE ABOUT
HORIZONTAL AXIS

Joseph K. Rose, Chicago, Ill.

Application December 27, 1946, Serial No. 718,850

1 Claim. (Cl. 178—7.5)

1

This invention relates to a television receiver or other viewing apparatus, such as a projector having a self-contained screen, and particularly to means to adjust the angularity of the viewing screen in accordance with the conditions surrounding the reception of the televised images and to means for shielding the viewing screen from extraneous light.

Images displayed on a viewing screen, as in a television receiver, can be viewed most perfectly when the eyes of the observer are near a line perpendicular to the center of the plane of the viewing surface of the image exhibiting member. Within a certain distance from this line viewing is considered satisfactory. This satisfactory viewing space in front of the image exhibiting member is contained within the confines of a truncated figure whose cross sectional area is approximately the same shape as the viewing screen, that is, rectangular with rounded corners. These sections become increasingly larger as the distance from the screen increases. The longitudinal axis of this truncated figure is the above mentioned perpendicular to the center of the image exhibiting member. Television receivers heretofore known have had fixed viewing screens, incapable of adjustment except by the process of moving the entire cabinet housing the receiver.

It is an object of this invention to provide means for adjusting the angularity of the viewing screen by rotating the screen, within predetermined limits, in one or more directions. It is another object of this invention to mount the image exhibiting member rigidly with a supporting shelf and an apertured front panel so that the assembly is movable as a unit relative to the cabinet. It is another object of this invention to provide light shields for the viewing screen that may be adjusted in accordance with the position of the viewing screen as well as the extraneous light conditions. Other objects of this invention will become apparent upon reading the following description in conjunction with the accompanying drawings, in which:

Figure 1 is a perspective view of a television receiver with the viewing screen pulled forward for viewing by seated viewers and the top section down to provide maximum top light shielding;

Figure 2 is a fragmentary perspective view showing the viewing screen pushed back a few degrees for viewing by standing viewers and the movable portion of the cabinet top raised angu-

2

larly to increase the vertical angle of vision without eliminating the top light shielding;

Figure 3 is a cross sectional view showing the movable shelf and panel mounting;

Figure 4 is a fragmentary cross sectional view showing the means of supporting the shelf for sliding movement;

Figure 5 is a detail elevational view of a modification showing a lifting jack structure for moving the shelf;

Figure 6 is a perspective view of another embodiment in which the image exhibiting assembly is pivoted adjacent its bottom;

Figure 7 is a fragmentary perspective of the cabinet shown in Figure 6 with the image exhibiting assembly raised;

Figure 8 is a cross sectional view showing the mounting of the image exhibiting assembly;

Figure 9 is a fragmentary cross sectional view showing the method of pivoting the image exhibiting assembly;

Figure 10 is a fragmentary perspective view of another embodiment in which the viewing screen assembly is slidably forwardly of the cabinet;

Figure 11 is a fragmentary perspective view showing the viewing screen assembly of Figure 10 in its forward position;

Figure 12 is a perspective view of another embodiment in which the viewing screen and related mechanism are mounted on an angularly movable shelf and panel assembly that is pivoted at the bottom of the front panel;

Figure 13 is a fragmentary perspective view of the embodiment of Figure 12 with the viewing screen moved forwardly;

Figure 14 is a cross sectional view through the embodiment of Figures 12 and 13 showing the Figure 12 position in solid lines and the Figure 13 position in dotted lines;

Figure 15 is a fragmentary perspective view of a television receiver in which the viewing screen is rotatable to vary the lateral angle of the screen;

Figure 16 is a fragmentary perspective view showing the viewing screen rotated slightly from the position shown in Figure 15;

Figure 17 is a rear perspective view of the interior of the television receiver showing the rotatable platform; and

Figure 18 is a detail perspective view of the means for holding the platform in any lateral position.

In the drawings, the reference numeral 2 indicates a television receiver cabinet having a front 3, a top 4, side walls 5 and 6, a back 7 and a base

8. A shelf 9 secured inside the cabinet has the television chassis 10 mounted thereon, as shown in Figure 3. Control knobs 11 are mounted on the front of the cabinet to operate the receiver. A movable assembly 12 comprising a panel 13 and a shelf 14 is pivoted to the front of the cabinet just above the control knobs 11. The panel 13 is provided adjacent its top with a handle 15 by means of which the assembly may be moved angularly between a nearly vertical position and a position approximately thirty degrees from the vertical. Sufficient friction is provided, by means hereinafter described, to hold the assembly in any position of angular adjustment within its range of movement.

An upright member 16 is positioned adjacent each side of the shelf 14. The uprights are secured to the shelf 9 in any suitable manner. The members 16 are each provided with a recess 18, as shown in Figure 4. The recess extends from adjacent the top of the member 16 to a point just above the shelf 14 when the shelf is in its lowermost position, and is curved slightly as shown in Figure 3. A block 19 is secured to the shelf 14 adjacent each recess 18. Each block 19 has a recess 20 extending inwardly from the side adjacent the slot 18. Preferably a cup shaped member 21 is secured in the recess. A coiled spring 22 is positioned in the member 21 and exerts outward pressure on a rod 23 which is positioned partly in the member 21 and extends into the recess 18. In order to maintain a smooth contact surface for the rod 23, the recess 18 is preferably provided with a U-shaped metal channel 24. The force of the spring 22 pressing the rod 23 against the metal channel creates sufficient friction against the movement of the assembly 12 to hold it in any angular position to which it may be moved.

The panel 13 is provided with an aperture 25 which is in registration with the front end 26 of a cathode ray picture tube 27 which is movable with the assembly 12. The front end 26 of the cathode ray picture tube is generally circular in cross sectional area but the aperture blocks out part of the edges so that the visible area appears to be substantially rectangular with rounded corners. This portion visible through the aperture 25 constitutes the image exhibiting member or viewing screen.

The top section 28, positioned over the panel 13, is hinged at its rear edge to the top 4. The underside of the top section 28 is curved, as indicated at 29, so that its inner surface is an arc coinciding with the path of travel of the top edge of the panel 13 when the top section is in its down position. Accordingly, no gap exists between the panel 13 and the top section 28 when the top section is down regardless of the angular adjustment of the image exhibiting member.

In the positions of the image exhibiting member shown in Figures 1 to 3 the panel 13 and the image exhibiting member 26 slope rearwardly and upwardly from the front of the cabinet just above the control knobs 11. In this position the inset portion of the side wall 5 and the center wall 17 act as partial side light shields and the top section 28 serves as a top light shield. As the image exhibiting member is moved backwardly about the pivot it may be desirable to raise the top section 28 to increase the upward angle of vision. The panel 13 has a flange 30 extending rearwardly from its top edge, as shown in Figure 3, to prevent any gap between the lower surface of the top section and the panel 13 as the

5

top section is raised angularly. The hinge of the top section has sufficient friction to hold the top section in any position of angular adjustment.

15 The angular adjustment of the front panel 13 and the tilting of the top section 28 are not necessarily related adjustments. If the viewers are seated in a darkened room it may be desired to tilt the top section upward to increase the angle of vision without changing the front panel position.

The top section 28 has a pair of fan shaped bellows 31 and 32 attached to its bottom surface adjacent its opposite lateral edges. When the top section is raised angularly the bellows 31 and 32 extend the side light shielding so as to prevent any extraneous light from passing between the top of the cabinet and the underside of the top section 28. In the down position of the top section the side light shields collapse into recesses 31' and 32' in the top of the side wall 5 and the center wall 17. If desired, the recesses may be positioned in the top section adjacent its lateral edges instead of in the walls 5 and 17.

20 Instead of the bellows 31 and 32, the side shields may be formed of a plurality of small interengaged sections or may be in the form of solid opaque sections.

25 The hinging of the top section makes it possible to reduce the height of the cabinet that would otherwise be required. The hinged top section provides an angle of vision sufficiently high to enable standing viewers to observe the screen with a relatively low cabinet. With a fixed top section the top would obscure the view of standing viewers unless it were positioned a greater distance above the image exhibiting member.

30 A modified structure is shown in Figure 5 in which positive control means is provided for moving the assembly 12 about its pivot. The control means is a lifting jack comprising a shaft 34 rotatably secured to a base 35 mounted on the shelf 9. The shaft is threaded, as indicated at 36, and a sleeve 37 is engaged with the threaded portion to move substantially vertically as the shaft is rotated. A pin 38, secured to the upper end of the sleeve extends into a recess 39 in the edge of the shelf 14' so as to move the unit 12 about its pivot as the pin moves substantially vertically. The shaft 34 is rotated by means of a gear 40 secured thereto which is engaged by a worm gear 41 mounted on a shaft 42 which extends through the side wall 5 of the cabinet. A wheel or knob (not shown) is fixed to the shaft 42 outside the cabinet so it can be rotated. It is obvious that the jack mechanism will maintain the unit 12 in any angular position to which it is moved. When the lifting jack is used the upright members 16 and their related structure may be omitted.

35 In the form of the invention shown in Figures 6 to 9, inclusive, a movable assembly 43, comprising a shelf 44, a front panel 45, and a top section 46, is pivoted to a pair of oppositely disposed uprights 47, as indicated at 48, Figure 8. The picture tube 49 and the chassis 50 are both secured in fixed relationship to the assembly and rotate about the pivot therewith. The shelf 44 is provided with upwardly extending flanges 51 at its lateral edges. Rods 52 each having a head 53 embedded in one of the flanges 51 extend through the flanges and through apertures 54 in the uprights 47. The head 53 is preferably hex-

agonal, but may be any non-circular shape, in order to prevent rotation of the movable assembly 43 relative to the rods 52. The rods turn freely in the apertures 54. A spring washer 55 is mounted on each rod 52 and a castellated nut 56 is screwed tightly against the washer and held in place by means of a cotter pin 57.

As shown in Figure 8, the pivot 48 is positioned just above the shelf 44 at a point between the center and the back of the shelf. Many of the parts on the front portion of the chassis base 50 are radio frequency coils which are relatively light in weight. The heavier parts such as power transformer and iron core chokes are mounted on the rear portion of the chassis base. If desired, lead weights may also be added to the rear portion of the chassis base in order to balance the movable assembly at a point close enough to the rear of the cabinet to obtain the desired angular adjustments in the space available.

The heavier units which are mounted on the rear of the chassis base are generally larger than the units mounted on the front. The rear portion of the chassis base is, therefore, reduced in height, as indicated at 58, so as to bring the center of gravity of the rear portion of the assembly down so that it will be on a straight line with the center of gravity of the front portion of the assembly and the pivot point 48. When the two centers of gravity and the pivot point are aligned pivotal movement of the assembly will not disturb the balance because the moment arms on both sides of the pivot will change proportionately as the assembly is moved about the pivot and both sides will remain substantially balanced. The friction of the spring washers 55 is sufficient to hold the assembly in any angular position to which it has been adjusted. The force required to move the assembly 43 about the pivot 48 is that required to overcome the friction in the assembly plus or minus whatever slight deviation may exist from perfect balance. It is obvious that the deviation from perfect balance must not exceed the friction.

In order to permit movement of the assembly 43 about the pivot 48, the top section 46 is beveled at its rear top surface, as indicated at 58 and the forwardly extending edge of the adjacent portion of the cabinet top 59 is complementarily beveled, as indicated at 60. The top edge of the front wall 61 just below the assembly 43 is beveled on the inside, as indicated at 62, so that an apron 63, attached to the front of the shelf 44, may extend into the cabinet when the assembly 43 is in its down position. When the assembly is moved upwardly the apron closes the space between the bottom of the assembly and the top of the front wall 61 just below the assembly. Instead of the solid apron 63 a collapsible bellows may be substituted. When a bellows structure is used the front wall 61 will preferably be provided with a recess into which the bellows may be collapsed.

In the embodiment hereinabove described, the top section 46 always projects forwardly of the front panel 45, as indicated at 64, to serve as a top light shield for the image exhibiting member 65. The overhanging portion 64 of the top also serves as a convenient means for moving the assembly 43 about its pivot. When the assembly is in its down position the inset sides 66 furnish side light shielding.

In Figures 10 and 11 a movable assembly 67 is mounted in a cabinet 68 by means of conven-

tional drawer slides and rollers. The assembly comprises a front panel 69, side panels 70 and a shelf (not shown). The chassis and picture tube are mounted to move with the assembly. The front panel is provided with a handle 71 to facilitate sliding of the assembly. When the assembly is in its inner position, as shown in Figure 10, the inset side walls 72 and the overhanging top section 72' serve as light shields for the image exhibiting member 73. When no light shielding is required, as in a darkened room, the assembly is pulled out to provide full usable angle of vision.

In the construction of Figures 12 to 14 the television chassis is divided into two parts, a portion 74 being mounted in the base 75 of the cabinet 76, and another portion 77 being mounted on a shelf 78. The shelf 78, the front panel 79, side walls 80 and the member 81, which constitutes a part of the front of the cabinet and is rigidly connected to the shelf and the front panel, constitute an assembly which is pivoted to the front of the cabinet at the joint between the member 81 and the shelf 78. A ledge 82 is secured to the back wall 83 of the cabinet to form a rest for the shelf 78.

In Figure 12 the assembly is in its innermost position with the image exhibiting member 84 in its extreme upward angle suitable for standing viewers and the inset side walls 85 providing side light shielding. When it is desired to lower the angle of vision the assembly is grasped at the top rail 86 and then pulled forwardly to the position shown in Figure 13. A bellows 87 is secured to a flange 88 extending rearwardly and downwardly from the top edge of the front panel 79. The other edge of the bellows is secured to a cross piece 89 secured in the cabinet. The bellows closes the gap between the top and upper sides of the assembly and the cabinet when the assembly is in one of its forward positions. If desired, the bellows may be replaced by a solid apron secured to the top edge of the panel 79 and to the rear of the side walls 80.

The assembly is easily tilted to any position as the weight is offset by any suitable counterbalancing system. In Figure 14 an upright 90 secured to the base 75 extends upwardly past the shelf 78. A bar 91 is secured to the edge of the shelf 78 and extends downwardly therefrom. A spring 92 has one end secured to the top of the upright 90 and the other end to the bottom of the bar 91 so as to constantly urge the assembly upward into its forward position. The force of the spring is not quite equal to the weight of the assembly so that a slight additional force is required to move the assembly. However, the pull of the spring is sufficiently close to the weight of the assembly so that it will, together with the friction in the hinge, hold the assembly in any adjusted position. The pull of the spring is greatest when the assembly is in the position of Figure 12 as the spring is extended the greatest amount. In the position of Figure 13 the spring pull is less, but less upward force is required as the center of gravity of the mass shifts towards the pivot. There is also a balancing force on the other side of the pivot as part of the assembly rotates beyond the pivot.

The positioning of the picture tube at an upward angle, as shown in the embodiment of Figures 12 to 14, instead of in a substantially horizontal position permits the use of a cabinet of greatly reduced depth.

In the embodiment of Figures 15 to 18, inclusive, means is provided for adjusting the image

exhibiting member laterally by rotating an assembly 93 pivoted at the center of its front end and mounted on rollers 94 at its rear. The platform 95, on which the chassis 96 and the picture tube 97 are mounted, has its sides tapering towards the rear, as indicated at 98, to provide clearance for lateral angular movement. The assembly 93 also includes a front panel 99 having an aperture 100 through which the image exhibiting member 101 may be viewed. The front panel 99 has a rearwardly extending top flange 102 and a pair of rearwardly extending side flanges 103 and 104. The front 105 of the cabinet adjacent the flanges 103 and 104 is also provided with rearwardly extending flanges 106 and 107. The flanges 102, 103, 104, 106 and 107 prevent access to the cabinet between the front panel 99 and the adjacent portions of the front 105 when the image exhibiting assembly 93 is in a laterally rotated position, as indicated in Figure 16. The flanges 103 and 104 are slightly rounded, as indicated at 108 and 109 to provide clearance when the assembly 93 is rotated from the straight forward position of Figure 15 to the laterally rotated position of Figure 16.

A rod 110 extends from the rear edge of the platform 95 and may be used as a handle to rotate the assembly 93 laterally within a range of about twenty degrees. A rounded, reinforced back 111 at the rear edge of the cabinet 112 is provided with a horizontally extending slot 113 through which the rod 110 extends. A wing nut 114 is threaded on the end of the rod 110 and can be tightened against the back 111 to positively hold the assembly 93 in any laterally adjusted position. It will be obvious that the shelf 115, Figure 17, upon which the assembly 93 is pivoted, may be constructed in accordance with the disclosure of the embodiments illustrated in Figures 1 to 9, inclusive, so that the assembly 93 may be adjusted vertically as well as laterally.

Although the illustrations in this application are of the direct viewing type of television receiver and the accompanying description is, for the most part, written for this type of receiver, the principles involved, of change of location or angle of image exhibiting assembly resulting in corresponding change of location or angle of image viewing screen, also apply to the projection, reflecting and other types of television receivers. In the projection receiver this movable

assembly would generally contain the reflecting mirror and the front viewing screen, while in the reflecting type it would contain the reflecting mirror.

While I have described a few preferred embodiments of my invention in considerable detail, it will be understood that the description is intended to be illustrative, rather than restrictive, as many details of structure may be modified or changed without departing from the spirit or scope of my invention. Accordingly, I do not desire to be restricted to the exact details described, except as limited by the appended claim.

I claim:

In a television receiver, a cabinet having a recess in the upper portion of its front wall, an assembly pivoted in said recessed portion to move about a single horizontal axis between a position within the normal confines of said cabinet and a position forwardly of said cabinet, said assembly including an apertured front panel and an image exhibiting member viewable through said apertured front panel in all positions within the range of movement of said assembly.
